CENTRIFUGAL SEPARATOR

John F. Tholl, Needham, Mass., assignor to
American Tool & Machine Co., Hyde Park, Bos-
ton, Mass., a corporation of Massachusetts

Application January 18, 1936, Serial No. 59,736

6 Claims. (Cl. 210—63)

This invention relates to centrifugal separators and similar machines.

It aims to devise a machine of this type which can be conveniently used in various treatments of solids, such as fabrics, yarn, fibers, and others. Such treatments are desirable in impregnating, dyeing, and many other operations, and the present invention proposes to utilize the action produced in a centrifugal in order to create the hydrostatic pressure desirable to promote the impregnation or other treating process, and to effect the separation of the treating liquid from the treated material and the discharge of said liquid from the separator.

15 The nature of the invention will be readily understood from the following description when read in connection with the accompanying drawing, and the novel features will be particularly pointed out in the appended claims.

20. In the drawing,

Figure 1 is a vertical, sectional view of the basket of a centrifugal separator constructed in accordance with this invention; and

Fig. 2 is a plan view of the basket illustrated in Fig. 1.

The construction shown in the drawing comprises a basket 2 of approximately cylindrical form but tapering slightly from its lower end toward its upper end. It may be supported for rapid rotation about a vertical axis in any suitable manner as, for example, in accordance with my prior Patent No. 2,018,474, although the arrangement illustrated in that patent for maintaining the casing substantially air tight usually is not required in the present invention. Such a supporting mechanism, however, includes suitable bearings for the vertical shaft on which the basket is mounted, and a casing or curbing encircling the basket to catch and carry away the liquid separated from the treated material.

The basket structure includes a central hollow column 3 through which the treating liquid may be introduced, this column being provided with ports 4 through which the liquid can flow freely into the main body of the basket. The upper and larger end of the basket normally is closed by a cover 5, the margin of which rests on a gasket 6, usually consisting of lead or some other suitable material. In order to hold the cover securely but yieldingly in its closed position, the central portion of this member is provided with a housing 7 in which a coiled spring 8 is mounted, the lower end of this spring bearing on the bottom of the housing, while its upper end bears against a washer 10 which, in turn, is backed up

by a hand nut 12 threaded on to the upper end of the column 3. A spring retaining ring 13 fitting into a groove in the wall of the housing 7 at its upper end prevents the washer from being forced out when this nut is backed up. Preferably the housing 7 is welded or otherwise rigidly secured to the cover 5.

In introducing the material to be treated into the basket, the cover is removed by unscrewing the hand nut 12, and when this loading operation has been completed the cover is returned to its initial position, as shown in Fig. 1. Thereafter the dye or other treating liquid is introduced into the basket through the column 3. The rapid rotation of the basket creates a very substantial hydrostatic pressure, directed radially, which is highly useful in producing a thorough and complete impregnation of the goods with the liquid, it being understood that the treated material naturally is held against the lining of the basket by centrifugal inertia, and that it is submerged in the treating liquid which assumes an approximately uniform radial depth in the basket. 10 15 20

When the goods have been subjected to the action of this liquid for the desired length of time, it then becomes necessary to discharge the liquid. In order to facilitate this operation, means has been provided to open the cover automatically and thus to permit the liquid to escape. For this purpose several bell crank levers 14 are pivoted, respectively, on pins 15 positioned in a ring 16 that is secured rigidly to, or is formed integrally with, the cover 5, each lever being mounted in a radial slot provided for it in the ring. Under the heel of each lever 14 is a pin 17 which forms the fulcrum for the lever, these pins being secured in and projecting upwardly from a collar 18 which is shrunk on, or otherwise rigidly secured to, the upper margin of the basket. These levers are so designed and weighted that they do not interfere substantially with the action of the spring 8 in maintaining the cover 5 closed at the normal operating speeds of the basket. When, however, it is desired to discharge the liquid, the speed of the basket is increased to an abnormally high value, and at this high speed the centrifugal force or centrifugal inertia of the levers 14 is sufficient to swing their upper ends outwardly, thus causing them to rock on their respective pins 17 and to lift the cover 5. As above stated, the basket is slightly tapered toward its upper end so that the hydrostatic pressure is greatest at this point and the liquid, therefore, flows out under the margin of the cover into the groove 20 in the collar 18 and

thence through a multitude of downwardly inclined ports 21, this liquid being caught by the surrounding casing or curbing with which these machines customarily are equipped.

5 The slight taper of the basket materially facilitates the draining of the liquid from the goods, but in order to promote this action and to produce a more efficient separation of the liquid from the solid material, the basket desirably is equipped 10 with a special lining. Preferably this lining consists of two foraminous layers, the inner of these layers serving to support the material under treatment and to permit the passage of the liquid radially through it, while the outer layer acts as 15 a spacer to separate the inner layer from the imperforate wall of the basket by a distance sufficient to permit the flow of the liquid under the action of centrifugal force along the wall of the basket toward its upper end. In the particular 20 construction shown the inner layer or lining member 22 consists of a perforated sheet of metal, while the spacing layer 23 consists of a woven wire fabric or screen of fairly coarse mesh. Thus 25 after the main body of the liquid has been discharged, the continued rotation of the basket throws the liquid still retained by the solid material through the lining sheet 22 into the screen 23 where centrifugal action forces it along the inner wall of the basket toward the upper end 30 of the latter and discharges it through the annular slot between the margin of the open cover 5 and the gasket 6.

The invention thus provides a centrifugal mechanism in which treatment of solids with 35 liquids can be produced rapidly and efficiently. The machine is especially useful in those processes which require the material to be subjected to the action of a series of liquids of different kinds or having different concentrations. It will 40 be evident that after the initial treatment with one liquid and the discharge of that liquid from the container, and the draining of the liquid from the goods, a second liquid can then be introduced through the column 3 without even stopping the 45 rotation of the basket. This liquid may subsequently be discharged and a third introduced, and so on, until the desired results have been produced.

Having thus described my invention, what I 50 desire to claim as new is:

1. In a centrifugal device, the combination of a receptacle comprising a separator basket and a cover therefor, said receptacle being revolvable around its own axis at a high speed, yieldable means for holding said cover closed, and means mounted upon said receptacle for rotation therewith, and operable by centrifugal force developed

by rotation of the receptacle, to control the opening movement of said cover.

2. In a centrifugal device, the combination of a receptacle comprising a separator basket and a cover therefor, said receptacle being revolvable 5 around its own axis at a high speed, yieldable means for holding said cover closed, and means mounted upon said receptacle for rotation therewith, and operable by centrifugal force developed by rotation of the receptacle, to release, and cause 10 said cover to open at abnormally high speeds.

3. In a centrifugal device, the combination of a receptacle comprising a separator basket tapered toward one end thereof and a cover for closing the larger end of said basket, said receptacle being revolvable around its own axis 15 at a high speed, yieldable means for holding said cover normally in a closed position, and means mounted upon said receptacle for rotation therewith, and operable by centrifugal force developed 20 by rotation of the receptacle, to move said cover away from the larger end of the basket to open it.

4. In a centrifugal device, the combination of a receptacle comprising a separator basket and a cover therefor, spring means for holding said 25 cover closed, and additional means mounted upon said receptacle for rotation therewith, said additional means being operable by centrifugal force developed by rotation of the receptacle to lift and open said cover against the action of said spring 30 means.

5. In a centrifugal device, the combination of a receptacle comprising a separator basket tapered toward one end thereof and a cover for closing the larger end of said basket, said receptacle being revolvable around its own axis 35 at a high speed, yieldable means for holding said cover in a closed position, and a plurality of pivoted levers mounted to revolve with the receptacle, said levers being so positioned as to operate 40 by centrifugal force developed by rotation of the receptacle to open the cover, at a substantially predetermined speed.

6. In a centrifugal device, the combination of a receptacle comprising a separator basket and a cover therefor, said receptacle being revolvable around its own axis at a high speed, yieldable means for holding said cover closed and weight means constructed and arranged, and mounted to rotate with the basket, in such manner as to 50 move outwardly under the influence of centrifugal force, and means operatively connecting said weight means to the cover in such manner as to move the cover to open position as a result of the outward movement of the weight means. 55

JOHN F. THOLL.
